(57) **CLAIM**

The ornamental design for a jug, as shown and described.

DESCRIPTION

FIG. 1 is a front perspective view, from above, showing my new design;

FIG. 2 is a rear perspective view, from below, of the claimed design;

FIG. 3 is a front elevation view of the claimed design;

FIG. 4 is a rear elevation view of the claimed design;

FIG. 5 is a left-side elevation view of the claimed design;

FIG. 6 is a right-side elevation view of the claimed design;

FIG. 7 is a top plan view of the claimed design; and,

FIG. 8 is a bottom plan view of the claimed design.

The dotted broken lines in the drawing views define features of the claimed design that are seen through a transparent/translucent material.
